UNITED STATES PATENT OFFICE

157,213

WALLPAPER MOISTENING MACHINE

George E. Stevens, Missoula, Mont.

Application March 22, 1949, Serial No. 1,543

Term of patent 14 years

(Cl. D9—2)

To all whom it may concern:

Be it known that I, George E. Stevens, a citizen of the United States, residing as Missoula, in the county of Missoula and State of Montana, have invented a new, original, and ornamental Design for a Wallpaper Moistening Machine, of which the following is a specification, reference being had to the accompanying drawing, forming part thereof.

Figure 1 is a perspective view of a wallpaper moistening machine, showing my new design.

Figure 2 is a top plan view thereof, and

Figure 3 is an end elevational view thereof.

I claim:

The ornamental design for a wallpaper moistening machine, as shown.

GEORGE E. STEVENS.
